(57) **CLAIM**

The ornamental design for a connector terminal, as shown and described.

DESCRIPTION

FIG. 1 is a top front perspective view of a connector terminal showing our new design;

FIG. 2 is a bottom front perspective view thereof;

FIG. 3 is an enlarged view of FIG. 1 as identified by region 3 of FIG. 1 with environment partially removed for clarity purposes;

FIG. 4 is an enlarged view of FIG. 2 as identified by region 4 of FIG. 2 with environment partially removed for clarity purposes; and,

FIG. 5 is a cross-section taken through line 5-5 of FIG. 3 thereof.

The broken lines immediately adjacent to the shaded areas represent the bounds of the claimed design and form no part thereof. The broken lines depicting the remainder of the connector terminal show features that form no part of the claimed design.
